(57) **CLAIM**

The ornamental design for a light head, as shown and described.

DESCRIPTION

FIG. 1 is a perspective view of a first embodiment of a light head;

FIG. 2 is a top view of the first embodiment of the light head;

FIG. 3 is a front view of the first embodiment of the light head, the opposite rear view being identical;

FIG. 4 is a side view of the first embodiment of the light head, the opposite side view being identical;

FIG. 5 is a bottom view of the first embodiment of the light head;

FIG. 6 is a perspective view of a second embodiment of the light head;

FIG. 7 is a top view of the second embodiment of the light head;

FIG. 8 is a front view of the second embodiment of the light head, the opposite rear view being identical;

FIG. 9 is a side view of the second embodiment of the light head, the opposite side view being identical; and,

FIG. 10 is a bottom view of the second embodiment of the light head.

The broken lines shown in the figures represent portions of the light head that form no part of the claimed design.
